United States Patent Office

Des. 198,950
Patented Aug. 18, 1964

198,950

TRASH RECEPTACLE OR SIMILAR ARTICLE

Morton Hollis, West Newton, Mass., assignor to United Plastic Corporation, Fitchburg, Mass., a corporation of Massachusetts

Filed Dec. 16, 1963, Ser. No. 77,817

Term of patent 14 years

(Cl. D58—17)

FIG. 1 is a view in front elevation of a trash receptacle or similar article, showing my new design;

FIG. 2 is a view in side elevation thereof;

FIG. 3 is a top plan view, and

FIG. 4 is a section on line 4—4 of FIG. 2.

The opposite sides are the same as those shown.

I claim:

The ornamental design for a trash receptacle or similar article, as shown and described.
